JOHN L. KNOWLTON, OF PHILADELPHIA, PENNSYLVANIA, ASSIGNOR TO
HIMSELF AND WILLIAM H. BURR, OF SAME PLACE.

Letters Patent No. 106,374, dated August 16, 1870.

IMPROVEMENT IN LATH-MACHINE.

The Schedule referred to in these Letters Patent and making part of the same.

To all whom it may concern:

Be it known that I, JOHN L. KNOWLTON, of Philadelphia, in the county of Philadelphia and State of Pennsylvania, have invented a new and improved Lath-Sawing Machine; and I do hereby declare that the following is a full, clear, and exact description thereof, which will enable others skilled in the art to make and use the same, reference being had to the accompanying drawing forming part of this specification, in which—

Figure 1 represents a front elevation of my improved lath-sawing machine.

Figure 2 is a plan or top view of the same.

Figure 3 is a detail vertical transverse section of the same, taken on the plane of the line x x , fig. 2.

Similar letters of reference indicate corresponding parts.

This invention relates to a new construction of machine for sawing laths, pickets, &c., and consists in the application of vertically adjustable guides, which hold the sawed pieces, and prevent them from springing or twisting on the saws.

A, in the drawing, represents the frame of my improved sawing-machine.

B is the main shaft hung in the same.

Upon the shaft are mounted the circular saws C C, which are so placed that the teeth are all in line, so that they can all be filed and ground at one operation.

On the frame A are also the bearings of the feed-rollers D D, and of the discharge-rollers E E, the shafts of which receive rotary motion by suitable mechanism.

The feed-rollers are set somewhat oblique, their outer ends being nearer the shaft B than the inner, so that they will tend to crowd the stuff against the main guide or fence a , preventing it from working outward away from the saws.

This inclination of the feed-rollers need be but slight for all ordinary purposes, as even then it will suffice to hold the stuff in the desired position.

F F' are toothed guides arranged on the frame A close to the saws, the teeth on them being as far apart from each other as the saws.

These guides serve to hold the sawed laths or pickets apart and straight, preventing them from bending or twisting and from crowding the saws.

The upper guide F' is made vertically adjustable in a slotted arm, b , that projects from the frame, while the lower guide can be affixed, or part of the sawing platform c , as shown.

The feed-rollers are vertically adjustable in the ordinary or suitable manner.

Having thus described my invention,

I claim as new and desire to secure by Letters Patent—

The toothed or ribbed guides F F', arranged in combination with a gang-saw, substantially as and for the purpose herein shown and described.

JOHN L. KNOWLTON.
